His Attorney.

UNITED STATES PATENT OFFICE.

HERMANN H. LOTT, OF ST. LOUIS, MISSOURI.

LINK FOR BRACELETS OR THE LIKE.

1,192,917.

Specification of Letters Patent.

Patented Aug. 1, 1916.

Original application filed May 24, 1915, Serial No. 30,022. Divided and this application filed December 17, 1915. Serial No. 67,416.

To all whom it may concern:

Be it known that I, HERMANN H. LOTT, a citizen of the United States, residing at the city of St. Louis, State of Missouri, have invented certain new and useful Improvements in Links for Bracelets or the like, (being a division from my application for Letters Patent for links for bracelets or the like, filed May 24, 1915, Serial No. 30,022,) of which the following is a specification, reference being had to the accompanying drawing, forming a part thereof.

This invention relates generally to jewelry and, more particularly, to certain new and useful improvements in jewelry of that class or kind known as bracelets or wrist-ornaments.

The principal object of my present invention is to provide a comparatively simple and inexpensive catch or lock, whereby a plurality of the so called links in said application shown and described may be conveniently and detachably fastened upon the wrist when in connected or bracelet form.

With the above and other objects in view, my present invention resides in certain novel features of form, construction, arrangement, and combination of parts, all as will be hereinafter described and afterward pointed out in the claims.

In the accompanying drawing, which shows my present invention in preferred form, Figure 1 is a side elevational view of a plurality of jewelry links in connected or bracelet form fastened together to embrace the wrist by means of my new end catch or lock; Figs. 2 and 3 are plan views of parts of the jewelry link with which my new end-catch is adapted to be employed; Fig. 4 is a plan view of the catch or wrist-fastening member of the completed or finished bracelet shown in Fig. 1; and Fig. 5 is an inverted plan view, partly broken away, of one of the links, showing a second link provided with the catch or wrist fastening member shown in Fig. 4 operatively attached thereto.

Referring to the said drawing, in which like reference characters refer to like parts throughout the several views, A indicates one of the bracelet-links, which is preferably, as seen in Figs. 1 and 5, approximately rectangular in shape and slightly curved or arched longitudinally.

The link A comprises or includes a body-member, shell, or casing preferably of any suitable metal stamped or cupped to pro-

vide an outer top portion or wall 1, upon which in the finished link may appear any suitable or desirable design, ornamentation, or the like, and laterally disposed or flanged side portions or walls 2-2, and end-portions or walls 3-3', both end-portions or walls 3-3' being cut away, as at 4, for purposes hereinafter appearing.

Fitting flatwise snugly within the confines of the body-member or shell of the link upon the under or inner face of top wall 1 thereof, is a plate 5 preferably of sheet metal, plate 5 being provided adjacent one end thereof and preferably integrally, as by punching or the like, with an obliquely outwardly disposed spring or strap-engaging member 6.

Fitting flatwise upon plate 5 within the confines of the shell or body-member of the link, is a second plate 7 cut away at one end, as at 8, to provide an approximately U-shaped guide-frame embracing and surrounding the spring 6 of plate 5, the legs 9-9' of frame 8 being presented toward one end, as for instance, end 3, and which, for purposes of description, I will call the female end of the link. As seen particularly in Fig. 5, frame 8 of plate 7 has a width approximately the same as the width of cut 85 away portion or opening 4 in end wall 3 of the link. For purposes shortly appearing, one leg, as, for instance, leg 9, of frame 8 is lengthwise cut away on its inner side to provide at the outer end thereof a shoulder 90 or lug 10 presented toward the other or opposite leg 9' of said guide-frame.

The plate 7 is somewhat shorter in length than plate 5, whereby I provide a space, as at 11, at the opposite or, as I will call it, the male end of the link. Within this space and endwise abutting against plate 7, is the inner or pintle end of a flat link-attaching member or strap 12 fully described in said application and which, as in said application also fully described, is adapted to fit within the frame 8 and co-engage with the spring 6 of a second link A to detachably fasten link A and said second link A together. Similarly fitting within the space 105 11 and endwise abutting against the plate 7 of a third link A, as seen particularly in Fig. 5, is the inner or pintle end of my new end-catch or fastening member 13. This catch or member 13 projects longitudinally outwardly of the shell of the link through the cut away portion or opening 4

in end wall 3' of the shell and at its inner end is provided with laterally extending oppositely disposed pintle-lugs 14—14 which hingedly engage with end wall 3' of the 5 link-shell, as seen in Fig. 5. Also snugly fitting flatwise within the confines of the shell of the link and upon and covering plate 7 with its frame 8 and also the pintle-end of catch 13, is a third or shell-closing 10 plate or wall 15 cut away at one end, as at 16, to permit of some hinged or swinging movement of member 13 relatively to the shell of the link, side walls 2 and end walls 3—3' of the shell being crimped or inturned 15 upon the outer face of plate 15 to not only secure member 13 to, but also retain the plates 5 and 7 rigidly within, the shell or body-member of the link.

The member 13 is flat upon its opposite 20 faces and of such size relatively to the frame 8 of the link A as to endwise slidably fit therein, member 13 being lengthwise cut away or kerfed, as at 17, to provide a sidewise yieldable or spring portion 18 having a recess 19 to releasably engage with shoulder or lug 10 of leg 9 of the frame 8. Opposite spring portion 18, member 13 is provided with an outwardly projecting portion or shoulder 20.

30 In use or operation, on catch or member 13 being slidably inserted into the female end of the link A, as illustrated in Fig. 5, spring portion 18 thereof will engage at its recess 19 with said shoulder 10, shoulder or 35 projection 20 at the same time engaging upon the end wall 3 of the link A, said link A and said third link A being thereby releasably locked securely together. On proper pressure being applied upon the projecting head 21 of spring portion 18 of the member 13, spring-portion 18 will be disengaged at its recess 19 from the shoulder or lug 10 of the frame, when the said links 40 may be at once readily detachably disconnected.

45 While I have herein shown and described my invention in connection with a bracelet-link or links, for which use it is especially adapted and designed, it is to be understood that the same may equally well be applied 50 to other jewelry articles or the like, and that changes in the form, construction, arrangement, and combination of the several parts thereof may be made and substituted for 55 those herein shown and described without departing from the nature and principle of my invention.

Having thus described my invention, what I claim and desire to secure by Letters Patent is:

60 1. In a jewelry article, a link comprising

spaced apart top and back walls and side and end walls therebetween, one of said end walls being cut away to provide an opening into the link and the link being provided 65 interiorly adjacent said opening with a laterally projecting lug, and a fastening-member adapted to normally fit snugly through said opening and within the link, said member being cut away inwardly from one side 70 edge and then forwardly to integrally provide a spring-portion sidewise yieldable in the plane of said member, said spring-portion being recessed at one side edge to releasably engage with said lug when said 75 member is within the link.

2. In a jewelry article, a link comprising spaced apart top and back walls and side and end walls therebetween, one of said end walls being cut away to provide an opening 80 into the link and the link being provided interiorly adjacent said opening with a laterally projecting lug, and a fastening-member adapted to normally fit snugly through said opening and within the link, said member being cut away on a gradual curve inwardly from one side edge and then forwardly longitudinally of the member to integrally provide a spring-portion sidewise yieldable in the plane of said member, said 85 spring-portion being recessed at one side edge to releasably engage with said lug when said member is within the link.

3. In a jewelry article, a link comprising spaced apart top and back walls and side 90 and end walls therebetween, one of said end walls being cut away to provide an opening into the link and the link being provided interiorly adjacent said opening with a laterally projecting lug, and a fastening-member 95 adapted to normally fit snugly through said opening and within the link, said member being cut away on a gradual curve inwardly from one side edge and then forwardly longitudinally of the member to integrally provide a spring-portion sidewise 100 yieldable in the plane of said member, said spring-portion being recessed at one side edge to releasably engage with said lug when said member is within the link, said 105 member being provided at the free end of its said spring-portion and upon its side opposite thereto with a pair of oppositely disposed laterally projecting enlargements adapted to engage upon the end wall of the 110 link at opposite sides of said opening when said member is within the link and said spring-portion thereof in engagement with said lug.

115 In testimony whereof, I have signed my name to this specification.

HERMANN H. LOTT.
